THEODORE PICKERING, OF BATAVIA, NEW YORK, ASSIGNOR TO DOEHLER DIE-CASTING CO., A CORPORATION OF NEW YORK

METHOD OF CASTING CYLINDER HEADS

Application filed August 28, 1929. Serial No. 388,904.

My invention relates to a method of casting cylinder heads for internal combustion engines. In particular, the invention contemplates a method whereby permanent molds are used in casting cylinder heads for air cooled internal combustion engines.

Owing to the irregular contour of a cylinder head for an air cooled internal combustion engine, the formation of a suitable mold in which to cast the cylinder head presents numerous difficulties. The cylinder head has a clearance cavity in its bottom, the sides of which are undercut in one transverse axis. Elbow inlet and outlet passages communicate with the clearance cavity, and lateral spark plug openings are provided in opposite walls of the cylinder head and open into the clearance cavity. The outer surface of the side wall of the cylinder head is provided with circumferential heat radiating or cooling fins and the top wall has a plurality of parallel heat radiating fins disposed transversely to the inlet and outlet passages.

Heretofore, such cylinder heads have been cast in sand molds in the usual manner, that is, by forming a sand mold for each casting and pouring the metal into the mold. These sand molds which are reproduced for each casting require considerable care in the making as the protruding portions which form the heat radiating fins are delicate and easily broken and distorted. Castings produced in such molds are, in general, rough and uneven and require considerable machining to remove the roughness therefrom.

In accordance with my invention, I am enabled to produce a cylinder head for air cooled internal combustion engines which is smooth and accurate and requires no subsequent machining operations. I utilize a method for casting cylinder heads in which permanent molds are employed.

My method enables me to employ a permanent collapsible core for forming the undercut clearance cavity in the bottom of the cylinder head.

Other features and advantages of the invention will hereinafter more particularly

appear, and the invention will be pointed out in claims.

In practicing my invention, I employ a bedplate upon which the casting is adapted to rest, and a two-part permanent mold which is separable on a plane that is normal to the fins extending from the top of the cylinder head. A three-part collapsible core, which is complementary in shape to the clearance cavity, is inserted in and supported by the mold. Disintegratable cores complementary in shape to the inlet and outlet passages are supported at one end by the bedplate and with their other ends contact with the clearance cavity core. Lateral spark plug cores and longitudinal valve stem cores are also inserted in and supported by the mold, the spark plug cores contacting with the clearance cavity core and the valve rod cores contacting with the cores of the inlet and outlet passages. Into the assembled mold, the metal, consisting of an alloy of aluminum, is poured. The three-part core is then collapsed and removed, and the spark plug and valve rod cores are removed. The mold is then opened and the casting lifted from the bedplate, and the cores in the elbow passages are disintegrated and removed.

The method will be further explained in connection with the construction of mold illustrated in the drawings in which:

Fig. 1 is a side elevation of a cylinder head cast in accordance with my invention;

Fig. 2 is a longitudinal section of the same;

Fig. 3 is a transverse sectional elevation of a mold, showing the parts of the mold separated after a cylinder head has been cast; and

Fig. 4 is a longitudinal sectional elevation of the same taken on the line 4-4 of Figure 3.

In the drawings, there is represented a cylinder head for an air cooled internal combustion engine, the casting of which head will serve to illustrate the invention. The cylinder head is composed of an alloy of aluminum and is adapted to rest on the head end of the cylinder, the bottom 1 being secured

in sealing contact with the edge of the cylinder. A clearance cavity 2 is provided in the bottom, the sides 3 of which are undercut in one transverse axis as at 4. Aligned and oppositely opening inlet and outlet passages 5 and 6 of elbow shape and opposed lateral spark plug openings 7 in the walls 3 communicate with the clearance cavity 2. The outer surface of the side wall 3 of the cylinder head is provided with a plurality of circumferential heat radiating fins 8; similar fins 9, disposed transversely to the line of the inlet and outlet passages 5 and 6, are provided on the outer surface of the top wall 10. Through the top wall 10, valve stem openings 11 are provided and communicate with the inlet and outlet passages.

The mold in which the cylinder head is cast comprises a bedplate 12 and two parts 13, separable on a plane normal to the fins on the top of the cylinder and containing the center lines of the inlet and outlet passages. The bedplate 12 has a flat surface 14 which is complementary to the flat surface 15 above

the inlet passage 5 of the cylinder head, and a flat surface 16 which is complementary to the surface of the boss 16' around the exhaust valve stem opening. Upon these surfaces 15 and 16, the cast cylinder head rests when the two parts of the mold are separated. At either end of the bedplate there is provided a recess or print which receives complementary prints 17 on extended ends of the disintegratable cores 18 and 19 which, with the valve stem cores 20 and 21 extending through the bedplate, support the cores 18 and 19. The cores 18 and 19 are complementary in shape to the elbow inlet and outlet passages in the cylinder head. The separable parts of the mold have surfaces complementary to that portion of the top of the cylinder head which is between the flat surfaces 15 and 16 and at the right of the flat surface 16 as viewed in Figure 4, and also have surfaces complementary to the sides of the cylinder head. As the two parts 13 are brought together they form, with the bedplate, a mold about the inlet and outlet cores which mold is complementary to the outer surface of the cylinder head.

The meeting faces of the mold parts 13 have three complementary semicylindrical grooves outside the mold cavity, two of the grooves extending laterally and being aligned and opposed to each other, and the third being in the top at right angles to such line. The lateral grooves form cylindrical openings for the cores 22, and the grooves in the top together form a cylindrical opening for the collapsible core which is complementary to the clearance cavity in the cylinder head.

The collapsible core which forms the undercut clearance cavity in the bottom of the cylinder head comprises three parts, a cen-

tral part 23, and two side parts 24. Each of the three parts is provided with a handle 25 by means of which handles they may be inserted in the mold and withdrawn from the casting. The two side parts are provided with projections 26 which are complementary to the undercut recesses in the cylinder head. The central part 23 has converging side faces which act as a wedge between the side parts 24. In placing the core in the mold the two side parts 24 are inserted first, the amount which they will extend into the mold being determined by lateral flanges 27 which engage the opening in the mold and also the ends of the cores 18 and 19 with which they contact. The central portion 23 is then placed between the two side parts 24 and pushed into the mold until the lateral flange 28 extending therefrom abuts against the edge of the opening in the mold. The spark plug cores are then entered through their openings to contact with the side parts 24 of the clearance cavity core.

The cores 22 extend to the base of the projections on the mold which form the circumferential fins on the cylinder head. The aforementioned spark plug cores 29 extend in contact with the collapsible core forming the clearance cavity in the cylinder head through an opening bored in the respective cores 22. The edges of the cores 22 form a flat surface adjacent the fins around the spark plug opening against which the flange on the spark plug (not shown) abuts.

Into the mold or die assembled as hereinbefore described the metal is poured, the parts of the mold being held together by the usual clamping members 30. After the metal has been poured the various permanent cores are removed and the dies are separated. The cast cylinder head is then lifted from the bedplate 12 and the mold prepared for another casting. The casting is subsequently heat treated which facilitates the disintegration and removal of the cores in the elbow passages.

The molds are permanent, being made of steel, and produce accurate castings which eliminate subsequent machining.

It is obvious that the order of the steps may be modified and that various changes may be made in the illustrated embodiment of the apparatus used in carrying out my method within the principle and scope of the appended claim.

I claim:

The method of forming a cylinder head for air cooled internal combustion engines which head is composed of an aluminum alloy and has a clearance cavity in its bottom, the sides of which are undercut in one transverse axis and which has elbow inlet and exhaust passages opening into the top of the cavity and lateral spark plug openings into the cavity and a plurality of cir-

cumferential cooling vanes and a plurality of parallel top cooling vanes disposed transverse to the said passages, which method consists in employing a permanent mold the parts of which are separable on a plane normal to the top vanes, inserting a three-part core axially in the mold cavity complementary in shape to the clearance cavity, inserting two lateral cores for the spark plug openings, supporting two distintegratable cores in the bottom of the mold complementary in shape to the elbow passages, pouring the metal into the mold cavity, then collapsing and removing the three-part core and withdrawing the cores for the spark plug openings, opening the mold and removing the casting, and disintegrating the cores in the elbow passages.
